AUTOMATIC TRAIN PIPE CONNECTER

Clifton B. Herd, Los Angeles, Calif., assignor to
 Johnson Connector Company, Ltd., Los Angeles,
 Calif., a corporation of California

Application April 1, 1935, Serial No. 14,108

8 Claims. (Cl. 285—24)

This invention relates generally to automatic train pipe connectors. The device of the present invention is of the same general type as that disclosed in Patent No. 1,896,687, issued to Albert S. Johnson, and may be considered generally as consisting of improvements on the connector shown in said patent. Reference is also directed to Patent No. 1,990,652 issued to Albert S. Johnson, and to my copending application entitled "Draw bar guide for automatic train pipe connector", filed February 7, 1933, Ser. No. 12,842, said patents and application including generic and specific claims to subject matter shown and described in the present application.

It may be stated as an object of the present invention to provide improvements in an automatic train pipe connector of the type involving separate air and steam heads, pipe connector heads, and to provide improved means for guiding such heads into connection.

It is a further object of the invention to provide a train pipe connector of the type involving separate air and steam heads with an improved air and steam head mounting on the connection arm end with improved means of assembly of the heads on the arm.

In accordance with the present invention separate air and steam connector heads are separately pivoted on a mounting knuckle on the forward end of the connector arm, preferably on a common axis, the steam head preferably being placed below the air head. Means are provided on the air heads for gathering together from positions of comparatively wide misalignment. There is also provided a horizontal guiding connection between each air head and the steam head below it, so that any pivotal action of the air heads which may be necessary in coupling (for example, if the coupling is being made on curved tracks) will be transmitted to the steam heads to cause them to pivot correspondingly, thereby causing them to couple more easily. Consequently, the steam heads are guided and gathered together through the gathering action of the air heads.

The invention will now be most readily understood by referring to the following detailed description of a present preferred embodiment thereof, reference for this purpose being had to the accompanying drawings, in which:

Fig. 1 is a side elevation of the meeting ends of a pair of coupled cars equipped with the devices of the present invention;

Fig. 2 is a side elevation showing the connector of the present invention;

Fig. 3 is a vertical transverse section taken on line 3—3 of Fig. 2;

Fig. 4 is a vertical transverse section taken on line 4—4 of Fig. 2;

Fig. 5 is a section as indicated by line 5—5 of Fig. 2;

Fig. 6 is a vertical longitudinal section of the coupler arm and a portion of the air and steam heads;

Fig. 6a is an enlargement of a portion of the connector arm shown in Fig. 6;

Fig. 6b is a section taken on line 6b—6b of Fig. 6a;

Fig. 6c is a section taken on line 6c—6c of Fig. 6a;

Fig. 7 is a section taken on the broken line 7—7 of Fig. 6;

Fig. 8 is a section taken on broken line 8—8 of Fig. 1;

Fig. 9 is a plan view of one of the steam heads;

Fig. 10 is a view showing the air and steam heads in front elevation, being a view looking towards said heads from the left in Fig. 2;

Fig. 11 is a view taken as indicated by line 11—11 of Fig. 2;

Fig. 12 is a section taken as indicated by line 12—12 of Fig. 5;

Fig. 13 is a section taken as indicated by line 13—13 of Fig. 6; and

Fig. 14 is a detail section taken as indicated by line 14—14 of Fig. 8.

In Fig. 1 of the drawings, numerals 20 and 21 designate a pair of cars coupled by a usual draft coupling 22, the interlocking heads 23 of which are mounted on draw bars 24. The draw bar coupler heads, as usual, have considerable gathering range enabling them to couple from positions of relative lateral, vertical and rotative displacement. The draw bars may be mounted to swing horizontally in any usual manner, either pivoting on vertical pins, or floating laterally on suitable guides (Fig. 2). In the case of passenger equipment, centering springs are used on the draw bars, as indicated at 26 in Fig. 1.

Rigidly fixed to the understructure of the car 45 body is a suspension bracket 29 for the train pipe connector, generally designated at 30. To the underside of bracket 29 is secured by screws 31 a hanger 32 that provides a vertical pivot bearing for the connector arm mounting. This 50 bearing has a bore 33 extending upwardly from its lower end, a bore 34 extending upwardly from the upper end of bore 33, and a larger counterbore 35 extending downwardly from its upper end to meet bore 34, all as clearly shown in Fig. 55

3. Mounted for rotation in bores 33 and 34 is the stem 36 of a yoke member 37. The upper end of said stem 36 has screwthreaded thereon a bearing ring 38, which overhangs the shoulder 39 between bores 34 and 35 and bears down on a washer 40 resting on said shoulder to support the yoke and parts mounted thereon.

The yoke is thus mounted in bearing hanger 32 for pivotal movement about a vertical axis. 10 Mounted for pivotal movement in the lower portion of yoke arms 37a and 37b are horizontal pivot studs or trunnions 41 and 42, respectively, which are formed integrally with and extend oppositely from a tubular cradle member 44 15 straddled by the yoke. This cradle member 44 supports a longitudinally extending connector arm tube or cylinder 46, the outer end of which carries an air pipe connector head 47 and a steam connector head 48, more fully to be de- 20 scribed hereinafter.

Cradle trunnion 42 is mounted for pivotal movement in a bore 50 provided in the lower portion of yoke arm 37b (Fig. 3). Cradle trunnion 41, on the other hand, is supported on its 25 lower half by a half-round bearing surface 52 formed in the lower portion of yoke arm 37a, while the upper half of said pivot stud has bearing against a half-round bearing surface 53 formed on a mounting casting 54 which is 30 mounted against the side of yoke arm 37a. Said casting 54 is secured in position by means of a pin 55 which is passed through a lug 56 formed on member 54 and through flanges 57 formed integrally with yoke arm 37a (see Figs. 2 and 3). 35 Cradle 44 and the connector arm carried thereby are mounted for pivotal movement about the horizontal axis of cradle pivot trunnions 41 and 42, while the cradle and connector arm may be swung horizontally by rotation of 40 yoke 37 on its vertical axis.

It will be evident from an inspection of the drawings that the described mounting for the pivot studs of the cradle in the yoke arms enables the device to be most easily assembled. An 45 opening 58 in yoke arm 37a permits the cradle to be lifted in from the bottom, with trunnion 41 at first on top, to a position somewhat above its final level, and then to be so manipulated that trunnion 42 enters bore 50 while trunnion 41 50 backs down and comes to rest on bearing surface 52 (see Fig. 3). Casting 54 is then pinned in place, and forms the upper half of the bearing for pivot stud 41, as previously described. To enable pivot stud 42 easily to enter bore 50 55 during the assembly, said bore may be relieved somewhat at the top, as indicated at 60.

For the purpose of supporting the connector arm in a normal position of horizontal extension, the pivot yoke member is provided with 60 a rearwardly extending and upwardly inclined bracket 61 providing coil spring seats 62, and cradle 44 is provided with oppositely extending bracket arms 63 and 64 which carry spring seats 65 opposite seats 62. Mounted on these 65 seats are compression springs 68, which are adjusted to support the connector arm yieldingly in a position of horizontal extension.

The forward end of cradle member 44 is formed with an enlarged box 70 (see Figs. 4 and 70 6). This box opens into the tubular portion of the cradle, as shown, and has at its forward end an opening 71 which freely passes the connector arm tube 46. Connector arm tube 46 is em- 75 braced and supported within this box by a forward and a rearward pair of upper and lower

rollers 72, which are rotatably mounted on shafts 74 rigidly mounted in the side walls 75 of the box. These rollers, which constitute the sole mounting for the arm tube within the supporting cradle, are provided with arm-tube en- 5 gaging surfaces 78 curved to the radius of the arm tube, and are preferably formed of some suitable anti-friction composition. This anti-friction provision reduces to a minimum wear on arm tube 46, which in service has more or less 10 continuous telescopic movement in and out of cradle 44.

Connector arm tube 46 has rigidly mounted on its forward end a yoke or knuckle 80 providing independent vertical pivot mountings for air pipe 15 connector head 47 and steam pipe connector head 48. This knuckle 80 includes a pair of vertically spaced and forwardly extending projections 81 and 82, respectively, the upper projection having a round upwardly extending boss 20 83, and the lower projection having a vertical bore 84 axially aligned with boss 83. The air connector head casting 47 is formed at its rear with a housing structure 86 for a locking device 25 hereinafter to be described. The upper wall of said structure is extended rearwardly to form a bracket 87, which is provided with a bore 88 adapted to rotatively receive knuckle boss 83, and the lower wall of the structure is extended rearwardly to form a bracket 89, which is provided with a round downwardly extending boss 90 adapted to be rotatively received in knuckle bore 84. Thus the air connector head 47 is vertically pivoted on the forward end of the connector arm. 30

The rear vertical wall 94 of the head (Figs. 6 and 7) is formed at right angles to the connector arm axis, and is cut away in the top and in the center to provide for a latch releasing device later to be described, leaving a pair of rear 40 wall portions or lugs 96 and 97, which present flat faces toward and at right angles to the connector arm.

The forward end of arm tube 46 has mounted therein a bushing 100, and mounted with a 45 sliding fit in said bushing is a buffer tube 102 having on its forward end a buffer head 103 adapted to engage rear wall lugs 96 and 97 of the connector head. The buffer head is preferably in the form of a plate having a bore therethrough 50 to take the forward end of tube 102, and may be fastened to tube 102 by welding. The buffer head engages the two head lugs 96 and 97, respectively, on opposite sides of the longitudinal connector arm axis, as appears from Fig. 7. The 55 rear end of tube 102 is formed with a pair of upper and lower rearward projections 108 which pass through slots 109 provided in an abutment 110 welded within bushing 100, as will be seen from Figs. 6a, 6b and 6c. These projections 108 60 engage against a washer 111, which come against one end of a compression spring 112, the other end of which spring bears against an abutment 113 fastened within the rear end of cradle member 44. It will be readily understood how any 65 pivotal movement of the connector head about the vertical pivot axis on the knuckle 80 is yieldingly resisted by spring 112 acting through the buffer member against head lugs 96 and 97, and it will be understood that spring 112 constantly 70 acts to return the connector head to a centered position when displaced therefrom. In the present embodiment the vertical pivot mounting of the connector head permits the head to swing, against the resistance of the spring urged buffer 75

member, to a maximum angle of approximately 30° on either side of the centered position illustrated in the drawings.

Spring 112, bearing at one end against abutment 113 in the rear end of cradle 44, and at the other end against buffer tube projections 108, also acts through the buffer tube and connector head to extend connector arm tube 46 from cradle 44. Such extensive telescopic movement of tube 46 from cradle 44 is opposed and limited as now to be described. The abutment 113 in the rear end of cradle 44 carries a tube 115 that projects through spring 112, the forward end of this tube having welded therein a head 116. This head 116 is cut through with a rectangular guide slot 117 for a flat tension rod 120, this rod being shown in cross section in Fig. 6b. The rear end of tension rod 120 has an enlarged head 121 adapted to engage head or abutment 116. The forward end of rod 120 passes through a guide slot 123 formed in an anti-friction composition insert 124 mounted within abutment 110. The forward end of flat rod 120 is reduced somewhat in width and its edges are screwthreaded, as indicated at 130, and screwthreaded thereon is a tubular member 135 that projects forwardly through buffer tube 102. The forward extremity of this reduced portion of flat rod 120 engages in a flat slot 137 formed in a key member 138 which is fastened to member 135, as at 139. This provision holds member 135 against rotation on rod 120. Member 135 has a rearwardly facing shoulder 136 affording a seat for one end of a compression spring 140, the other end of which bears against the forward end of insert 124 mounted in abutment 110 (Fig. 6a).

The position of Fig. 6 shows the normal uncoupled position of the connector arm. It will be apparent from that figure that spring 112 is acting against buffer tube 102 and through the connector head to extend connector arm tube 46 from cradle tube 44, and that such extension is resisted by tension rod 120, the head 121 of which engages fixed abutment 116, and the other end of which acts against abutment 110 through spring 140. It will thus be evident that spring 112 tends to extend the connector arm from the cradle, while spring 140 and tension rod 120 act in opposition, tending to contract the connector arm; as a result the connector arm takes a normal uncoupled position with springs 112 and 140 balanced against one another, as illustrated in Fig. 6.

Considering now the air connector head 47 in its preferred form, each air head has extending forwardly from the previously described housing structure 87 a vertical plate or tongue part 150 which crosses the longitudinal connector arm at an angle of about 30°. The head also has a part 154 forming a flaring guide mouth terminating rearwardly in a contracted throat 155, the guide mouth of each head being adapted to receive the tongue of the other head, so that surfaces 157 of the two tongues come into contact. The guide mouth formed by part 154 is defined by rearwardly converging side, upper and lower walls 158, 159 and 160, respectively, all tapering toward the open contracted throat 155. The forward portion of each tongue member 150 is formed with converging upper and lower edges 162 and 163, adapted to ride and be guided down or up the inclined walls 159 and 160 of the guide mouth of the opposing head into proper elevation for connection, while the side wall 158 of

the mouth gathers the tongue laterally into position.

Thus the tongue of each head moves into the guide mouth of the other head as the cars are moved together, the flaring of the guide mouth being sufficient to gather the head properly within in comparatively wide limits of misalignment.

Opening to contact surface 157 of each tongue 150 is a pair of air ports 175 that extends through the tongue. Air hoses 180 (see Fig. 1) may be 10 connected to said ports at the rear side of the tongue by means of clamping devices 181. These air ports are provided at the contact surface of the tongue with suitable gaskets in the usual manner.

The tip of each tongue 150 is formed with a projecting lug 194 which engages the face of the opposing tongue as the heads come together. The engagement of these lugs 194 with the opposing tongues causes the two heads to pivot 20 through a certain angle on their vertical pivot mountings on the supporting knuckles 80. As the heads continue to move together, the heads pivoting as described, the tongue lugs hold the tongues separated until the air port gaskets are 25 nearly alined, and then finally ride down seating surfaces 195 to permit the opposed tongues to come face to face and their gaskets to engage one another, the heads pivoting back to center position by action of the spring pressed buffer 30 members, and the parts finally taking the interlocked position of Fig. 7. It will be evident that this manner of interengagement of the heads avoids all possibility of the gaskets rubbing on 35 one another.

To hold the tongues against separative movement until the heads are to be disconnected, there is provided a latching device 198 which automatically engages over the ends of the tongues as the heads reach the interengaged position of Fig. 7. In the present preferred form, this latching device takes the form of a latch member 198 contained within the previously described housing structure of the head. The latch member is pivotally mounted on the head 40 at 200, and extends horizontally from said pivotal mounting to a hook end 206, which is adapted to hook over the forward end of the tongue of the opposing head. Latch 198 has intermediate its ends a lug 210 which provides a seat 50 for one end of a compression spring 211, the other end of which is supported by knuckle 80. This spring serves the purpose of constantly urging the latch toward latching position.

As previously stated, Fig. 6 shows the position 55 of the connector arm parts in uncoupled position. Fig. 2 shows the same position, and also shows that in uncoupled position the connector head extends outwardly somewhat beyond the end of the draw bar coupler head. As the cars 60 move together, the interengagement of the pipe coupler head causes the connector arm tubes 46 to recede within the cylindrical cradle members 44 against the force of springs 112 until the draft couplers engage. During this operation, the connector heads will have rocked on their pivotal 65 mountings on knuckles 80 against the spring pressed buffer plates as the two tongues interengaged and finally came into face to face contact, and the latches will have become hooked 70 over the tongue ends to lock the heads securely together, the parts then being in the position of Fig. 7. If the contact faces of the two tongues are not in the same vertical plane as the heads finally engage, the arm tubes rotate slightly to 75

allow them to come into face to face contact, such rotation being yieldingly opposed by torsion action of the flat rod 120 that connects arm tube 46 with the cradle. When the cars are 5 coupled the arm tubes 46 ride in a retracted position, the compression springs 112 being at such times under some compression. Small movements of the coupled cars as slack comes into 10 or is taken out of the draft connection is then absorbed by relative longitudinal movement of arm tubes 46 in cradle tubes 44, cushioned by springs 112.

To uncouple the cars, the draft coupler heads are released and the cars moved apart. Since 15 the pipe connector heads are still locked together, this causes the connector arm tubes 46 to be extended from the cradle tubes 44, as will be evident. For release of the latch, the tubular member 135 attached to tension rod 120 is 20 provided with a forwardly reaching hook member 215 which is adapted to engage the rear side of latch lug 210 and move the latch rearwardly to release the tongue during such extension of the connector arm. It will be evident that as 25 the arm extends, the head 121 of the tension 120 being in engagement with abutment 116, latch lug 210 finally engages hook element 215 and so causes relative rearward movement of the latch and consequent release of the connector 30 heads.

The extension of connector arm tube 46 during such uncoupling is yieldingly resisted by spring 140, and when the connector heads have disengaged, this spring 140 acts to cause retraction 35 of the connector arm to the normal uncoupled position shown in Fig. 6.

Figs. 3 and 5 show the provisions for limiting the horizontal swing of the connector arm. As there shown, the side wall of the pivot bearing member 32 is formed with a bore 220 within which works a locking plunger 221 which is adapted to be received within a notch 222 cut in the stem of pivot yoke member 37. Notch 222 is of sufficient horizontal length to permit the 45 pivot yoke stem to rotate through the angle necessary for proper swing of the connector arm, which may be for instance about ten degrees. Back of plunger 221 is a spring 223 which constantly urges the plunger into locking engagement with the pivot stem, and connected to the plunger and extending out through the side wall of bearing member 32 is a handle member 224, by means of which the plunger may be retracted to permit the connector arm to be swung beyond the limits permitted by notch 222. For instance, when it is desired to carry the connector arm in an inoperative position, the handle 224 is pulled and the connector arm rotated to a 50 position at about 72° from the center line of the car, another notch 225 being provided in the pivot stem to permit the arm to be locked in that position.

Preferably, means are provided for guiding the pipe connector arms to swing horizontally along 65 with horizontal swinging of the draw bars, so that if the draw bars are in such relative horizontal positions as to be capable of coupling, then the pipe connector arms will also be in such relative positions that the pipe coupling will positively be made.

Such a draw bar guiding arrangement was first disclosed and claimed in Patent No. 1,990,651 issued to Albert S. Johnson. The specific form of draw bar guide here illustrated and described is

more particularly shown and claimed in all its aspects in my copending application entitled Draw bar guide for automatic train pipe connector, filed March 25, 1935, Ser. No. 12,840.

The present illustrated draw bar guide is embodied as follows: Secured to the underside of draw bar 24 at a point thereon that swings horizontally to an extent sufficient for the purpose, is a depending guide arm 234, which in the present instance drops somewhat to one side of the 10 connector arm (see Fig. 5). This arm has a vertically extending portion 234a which is U-shaped in cross section (Fig. 5), and below said portion 234a the arm has a rearwardly extending portion 234b. As may be observed from Fig. 5, the opening 232 of the U-shaped portion of the arm faces toward the forward end of the connector. Rotatably received within bearing surfaces formed within this U-shaped opening 232 is the vertical pivot mounting pin 233 of a gate member 234 which is adapted to extend alongside guide arm extension 234b. Pin 233 has on its upper end an enlarged head 235, which seats downwardly against a shoulder 236 (Fig. 11) and so supports 25 the gate. When the device is first assembled, pin 233 is placed in the position described, and lugs 232a are then hammered in to the position shown to confine the pin against removal. Gate 234 has a latch lug 237 which is adapted to engage over the upper edge of arm extension 234b (Fig. 30 12), and when the parts are so engaged the adjacent surfaces 240 and 241 of members 234b and 234 define a slot or way 242 which receives the 35 forward end of a flat spring guide-member 245. This member 245 is mounted at its rear end on a supporting bracket 246 which is a part of the previously described mounting casting 54 mounted on the vertically pivoted yoke 37 (see Fig. 3).

Arm extension 234b is formed with a perforated lug 250 carrying a movable pin 251 which 40 overlies and engages the top side of gate 234 when said gate is in the closed position illustrated in the drawings (gate lug 237 engaged over the top of arm extension 234b, as in Fig. 12). At certain times it is desired to swing the entire connector arm to one side to an inoperative position, for instance in the event a car provided with the present equipment should be coupled to a car not so provided. In such event it is of course necessary to disengage guide member 245, which is 45 mounted on the vertically pivoted arm carrying yoke, from the draw bar suspended guide arm 234 and gate 234. This is accomplished by pushing back locking pin 251 until gate 234 is cleared, lifting the gate sufficiently that gate lug 237 clears 50 the top side of arm extension 234b, and then 55 swinging the gate to one side, whereupon member 245 is released.

It will be understood that horizontal swinging 60 of the draw bar acts through the draw bar guide arm and spring arm 245 engaged thereby, to rotate the arm supporting pivot yoke and thereby cause the connector arm to follow horizontal swinging of the guide arm and draw bar. This swing, however, is limited in extent to about 5° 65 on either side of center by the stop plunger 221 and notch 222 in the yoke bearing member; and when the draw bar swings to one side to an angle greater than that allowed the connector arm, the over-movement of the draw bar is taken up by 70 flexure of spring arm 245. The draw bar guide provisions as thus described place the pipe connector arms in such relative positions whenever a coupling is to be made that the air pipe connection is always accomplished if conditions are 75

sufficiently favorable that the draft coupling can be made, the gathering range of the air pipe connector head being sufficient to assure connection within the full range of misalignment of the draw bar heads from which the draw bars will gather and couple.

There has now been described in considerable detail a preferred draw bar guided train pipe connector to which the improved steam pipe connector heads of the present invention may be typically applied. It will become apparent that in many aspects the steam head of the present invention is particularly applicable to the type of connector now described, and depends upon that type of connector for many of its own operating characteristics. It is to be understood, however, that the present invention in all its aspects is not to be considered as limited to use with the specific air pipe connector and its mounting as here shown, but may be applied to other types of connectors as well.

The steam pipe connector head is designated generally at 48 in the drawings, and is mounted directly below the previously described air connector head 47. Head 48 is pivotally mounted, independently of air head 47, on the same knuckle 80 on which head 47 is pivoted, and on an axis preferably coincident with the pivot mounting of head 47 (see Fig. 6). In particular, the rear end portion 300 of head 48 is provided with upper and lower pivots or trunnions 301 and 302, respectively, pivot 301 being received within knuckle bore 84 and pivot 302 being received within a bore 303 formed in a mounting plate 304 which is detachably secured to the lower end of knuckle 80, and which supports the underside of the steam head. As illustrated in Figs. 7, 8 and 13, member 304 has a rearwardly extending shank portion 305 formed with a flat upper surface adapted to engage the flat lower end surface 306 of knuckle 80, and with side flanges 308 adapted to fit between parallel depending knuckle flanges 309. Member 304 is secured in position by means of a locking pin 310 which passes through flanges 309 and through a bore 311 in member 304. It will be evident that this construction permits convenient assembly and disassembly of the steam head with the mounting knuckle. It is to be noted that either the air head or the steam head may be assembled with the knuckle first, and that either head may be disassembled without disassembling the other.

Steam head 48 is thus mounted on knuckle 80 independently of air head 47 but is arranged for pivotal action on an axis common with that of the air head.

The steam head 48 includes a tongue 315 and a part 316 forming a gathering throat at the base of the tongue adapted to receive the tip of the tongue of a mating head and to guide it into final position. The obliquity of tongue 315 is made opposite to that of the tongue of the air line connector head, for the reason that the steam pipes on trains are ordinarily on the opposite sides of the cars from the air lines and the steam and air lines therefore cross at the central point of the connector heads.

The inner surface of each tongue 315 has a vertical contact face 317, to which opens a steam port 318 having a usual gasket 319. Gasket 319 is backed up by a gasket sleeve 320 received within port 318, which is clamped in place by a releasable clamp device 322 which engages back of sleeve shoulder 323 (Fig. 8). The steam pipe

324 is connected to sleeve 320 in the usual manner.

A locking plunger or wedge 330 is mounted to work in a slot or way 331 formed in the forward end of tongue 315, said slot extending parallel to tongue face 317. As indicated in Fig. 14, the rearward portion of plunger 330 is rectangular in cross section, and has at its end a boss 332 which works within groove 333. A compression spring 335 disposed within pocket 336 seats against the rear end of plunger 330 and tends to move the plunger to a fully extended position. Such extension of the plunger is limited, however, by means of a stop pin 337 which is mounted in the plunger and extends within the previously mentioned groove 333, this stop pin engaging shoulder 338 at the forward end of groove 333 to limit extension of the plunger. With pin 337 in engagement with said shoulder 338, the tip 339 of the plunger preferably is extended slightly beyond the end of the tongue plate. The forward end of plunger 330 is beveled on its outside surface, as at 340, so that the plunger takes the form of a wedge. This beveled surface is adapted to be wedged against a parallel seating surface 341 provided within the throat member 316 of the mating head.

As previously stated, the relations of the parts are preferably such that when stop pin 337 is against stop shoulder 338, the tip 339 of wedge 330 or plunger 330 is extended just slightly beyond the forward end of tongue 315. This is the position taken by the wedge when the connector head is uncoupled. As two of the heads come into interengagement during coupling of a pair of cars, the ends of the tongues engage stop shoulders 334 to position the steam heads and align the gaskets, and the beveled back surfaces 340 of the wedges engage the seating surfaces 341, the wedges moving rearwardly a short distance. This movement, which takes place against springs 335, brings the wedges to a position such as shown in Fig. 8, stop pins 337 then being somewhat to the rear of shoulders 338. Springs 335 act in this position to force the wedges tightly against seats 341, and the engaging faces of the mating heads are accordingly forced together and held tightly in contact. The tightness of this contact is always maintained, since wear between wedges 330 and seats 341 will simply allow the wedges to move slightly further ahead, but they will act to force the engaging faces of the mating heads into contact the same as before. It will be noted, for example, that shoulders 334 are formed so as not to interfere with wedges 340, which are permitted to wedge in tightly and may extend beyond stop shoulders 334.

The steam heads are of course prevented from separating due to action of the air head locks, but because of slack between the air and steam heads, there is some tendency for the steam heads to move apart. Such action is prevented by the steam head wedges, which tend to slip forward and maintain their wedging engagement with the seating surfaces 341 on the mating heads. The wedges thus maintain the engaging faces of the two heads pressed tightly into contact with each other throughout ordinary action of the coupler heads while coupled; but as the cars are pulled apart and the air head locks release, the wedges finally release the steam heads from each other and permit them to separate.

It will be observed from Fig. 8 that the angle between the line of engagement of the beveled wedge surface 340 with the seating surface 341, 75

and the axis of the steam passage through the head, is sufficiently large that the friction between the engaging surfaces prevents the wedges from being retracted to release the heads due 5 to any separative force applied in the direction of the steam passage by the steam itself. The angle is, however, such that separative force applied along the longitudinal line of the connector causes the heads to separate without difficulty.

Means are provided for yieldingly resisting pivotal movement of the steam heads from a normal centered position. For this purpose there is provided a buffer member in the form of a plunger 350 mounted to work in a horizontal bore 351 provided in the lower portion of knuckle 80 opposite the pivoted rear end portion 300 of the steam head (see Figs. 6 and 8). Head portion has faces 352 and 353, formed at right angles 20 to and one on each side of plunger 350, and these faces are adapted to be engaged by the two opposite vertical edges 354 and 355, respectively, of a buffer head 356 mounted on the forward end of buffer plunger 350.

25 The buffer head edge or surface 355 which engages steam head face 353, which face 353 is on the side of the buffer nearest the steam head tongue (Fig. 8), stands normally (when the steam head is centered) a short distance back of face 30 353, while the opposite buffer head edge 354 is in engagement with its steam head face 352 in that position of the steam head. This means that when the steam head is rocked to the right on its pivot mounting, it will immediately be resisted 35 by the spring-urged buffer member, which will act to return the head to center; but when the head is rocked to the left, it is not opposed by the buffer member until it has rocked through an angle of several degrees. This provision is 40 made because in rocking in the latter direction, the steam head is resisted by the steam pipe, and the air head is resisted by the rubber air hoses, which must be pulled out and compressed, respectively, by the heads in such action, thus fulfilling 45 the function of the spring pressed buffers. When the heads rock in the other direction, the steam pipe must be moved back and the air hoses are pulled out but the same resistance is not encountered in such action, and the spring pressed buffers are designed to come into action at once.

50 It has been described how the air and steam heads are independently pivoted on a common vertical axis on mounting knuckle 80, and it has also been described how each air head is provided 55 with a flaring guide mouth adapted to gather the tongue plate of the mating head from various positions of misalignment during coupling, and how the air heads rock on their knuckle mountings during such gathering and coupling. It has 60 further been described how the draw bars guide the connector arms in horizontal swing, so that the air heads will be brought to relative positions from which they will positively couple if the draw bar heads are in sufficiently close alignment 65 to couple.

In accordance with the present invention, the steam heads are caused to be brought together by virtue of the gathering action of the guided air heads. As well shown in Figs. 2, 9 and 10, 70 the upper edge of the steam head tongue is formed, near the forward end of the tongue, with a pair of lugs 370 and 371, which are adapted to receive between them, somewhat loosely, the lower edge of the lower wall or flange 160 of the air 75 head 47.

There is by this means imposed on the steam heads a guiding action derived from the fully controlled and guided air heads. For example, if the connector arms are not originally in alignment, but extend towards each other at somewhat 5 of an angle, as for instance if the cars are on a curved track, the mating air heads will gather together, and in so doing will rock toward each other on their knuckle mountings. It will now be evident that, due to the interconnection provided 10 between air head flange 160 and the steam head tongue, such rocking of the air heads will cause the steam heads to follow, and will consequently place the steam heads in better position for coupling. In particular, the action is to 15 throw the tongue plates of the steam heads toward parallelism with each other as the coupling is made. The forward end of the tongue of one steam head may engage the tongue plate surface 20 317 of the other, or may strike the guide flange 316a. In either case, the nose then moves immediately into the throat of the opposing steam head, finally taking such a position as shown in Fig. 8, with the locking wedge 330 operating in the manner described above. Corresponding 25 action is had with any conditions of misalignment of the air and steam heads. The air head gathering provisions are capable of bringing the air heads into proper mating connection from all types of initial misalignment which are encountered in practice, and in each instance, the action of the air heads during coupling is such as is proper to bring the steam heads guided thereby into proper coupling interengagement.

30 Thus the gathering action of the mating air heads places the steam heads in position to mate properly also, and the steam heads are caused to move into the interlocked position of Fig. 8. It sometimes occurs that before coupling one connector stands considerably elevated relative to 35 the mating connector, and that the tongue of the steam head of the first tends to catch within the guide mouth of the air head of the relatively lower connector. To avoid difficulty from this source, I provide the tongue plate 150 of each air 40 head with a lower notch 150a which is adapted to pass the steam head tongue downwardly whenever it happens to come initially within the guide mouth of the air head. The edges of this 45 notch, as well as the various surfaces of the 50 steam head tongue itself, are suitably beveled so that whenever the steam tongue does come within the guide mouth of the air head, it will readily slide through notch and move downwardly 55 into proper relation with the opposing steam head.

60 It is particularly to be noted that while I thus provide for a general horizontal guiding of the steam heads by the air heads during coupling, the air and steam heads are separately pivoted on the mounting knuckles, and the connection between the air and steam heads is comparatively loose rather than rigid. This feature is of utmost importance, it being highly desirable that the steam heads be maintained as far as possible 65 separate of the air heads. With such an arrangement, if the steam heads should leak and tend to part, the looseness of their connection with the air heads will prevent the interlocked air heads from being affected in such a manner 70 as to leak air.

75 It will be understood that while I have now described one preferred specific embodiment which the invention may assume in practice, the invention is not to be considered as limited to 75

the details of this embodiment since various changes may be made without departing from the spirit and scope of the appended claims.

I claim:

5. In a train pipe connector, the combination of a horizontally extending connector arm, a knuckle mounting on the forward end of said arm, an air pipe connector head mounted to pivot on a vertical axis on said knuckle mounting, said air pipe connector head having a contact part formed with an engaging face diagonal to the longitudinal line of the connector arm and to which opens an air conduit, and having also a flaring guide member adapted to gather and receive the contact part of an opposing air head, a steam pipe connector head below said air head pivotally mounted on a vertical axis on said knuckle mounting, said steam head having a contact part formed with an engaging face diagonal to the longitudinal line of the connector arm, but opposite to the diagonal air head engaging face, and to which opens a steam conduit, and guide means interconnected between the air head and the contact part of the steam head causing the steam head to pivot on its axis to follow horizontal pivotal action of the air head. 20
  2. In a train pipe connector, the combination of a horizontally extending connector arm, a knuckle mounting on the forward end of said arm, an air pipe connector head mounted to pivot on a vertical axis on said knuckle mounting, said air pipe connector head having a contact part formed with an engaging face diagonal to the longitudinal line of the connector arm and to which opens an air conduit, and having also a flaring guide member adapted to gather and receive the contact part of an opposing air head, a steam pipe connector head below said air head pivotally mounted on a vertical axis on said knuckle mounting, said steam head having a contact part formed with an engaging face diagonal to the longitudinal line of the connector arm, but opposite to the diagonal air head engaging face, and to which opens a steam conduit, and guide means interconnected between the flaring guide member of the air head and the tongue part of the steam head causing the steam head to pivot on its axis to follow horizontal pivotal action of the air head. 35
  3. In a train pipe connector, the combination of a horizontally extending connector arm, a knuckle mounting on the forward end of said arm, an air pipe connector head mounted to pivot on a vertical axis on said knuckle mounting, said air pipe connector head having a contact part formed with an engaging face diagonal to the longitudinal line of the connector arm and to which opens an air conduit, and having also a flaring guide member adapted to gather and receive the contact part of an opposing air head, a steam pipe connector head below said air head pivotally mounted on a vertical axis on said knuckle mounting, said steam head having a contact part formed with an engaging face diagonal to the longitudinal line of the connector arm, but opposite to the diagonal air head engaging face, and to which opens a steam conduit, and means on the contact part of the steam head engaging the flaring guide member of the air head, said means causing the steam head to pivot on its axis to follow horizontal pivotal action of the air head. 50
  4. In a train pipe connector, the combination of a horizontally extending connector arm, a knuckle mounting on the forward end of said
- arm, an air pipe connector head mounted to pivot on a vertical axis on said knuckle mounting, said air pipe connector head having a forwardly projecting tongue part formed with an engaging face diagonal to the longitudinal line 5 of the connector arm, and having on the side of said engaging face a flaring guide member adapted to gather and receive the tongue part of an opposing air head, a steam pipe connector head below said air head pivotally mounted on said 10 knuckle mounting on a vertical axis substantially coincident with the air head axis, said steam head having a forwardly extending tongue part formed with an engaging face diagonal to the longitudinal line of the connector arm, but opposite to the diagonal air head engaging face, and guide means interconnected between the air head and the tongue part of the steam head causing the steam head to pivot on its axis to follow horizontal pivotal action of the air head. 15
5. In a train pipe connector, the combination of a horizontally extending connector arm, a knuckle mounting on the forward end of said arm, an air pipe connector head mounted to pivot on a vertical axis on said knuckle mounting, 20 said air pipe connector head having a forwardly projecting tongue part formed with an engaging face diagonal to the longitudinal line of the connector arm, and having on the side of said engaging face a flaring guide member adapted to 25 gather and receive the tongue part of an opposing air head, a steam pipe connector head below said air head pivotally mounted on said knuckle mounting on a vertical axis substantially coincident with the air head axis, said steam head 30 having a forwardly extending tongue part formed with an engaging face diagonal to the longitudinal line of the connector arm, but opposite to the diagonal air head engaging face, and guide means interconnected between the flaring 35 guide member of the air head and the tongue part of the steam head causing the steam head to pivot on its axis to follow horizontal pivotal action of the air head. 40
6. In a train pipe connector, the combination of a horizontally extending connector arm, a knuckle mounting on the forward end of said arm, an air pipe connector head mounted to pivot on a vertical axis on said knuckle mounting, said air pipe connector head having a forwardly projecting tongue part formed with an engaging face diagonal to the longitudinal line of the connector arm, and having on the side of said engaging face a flaring guide member adapted to gather and receive the tongue part of an opposing air 55 head, a steam pipe connector head below said air head pivotally mounted on said knuckle mounting on a vertical axis substantially coincident with the air head axis, said steam head having a forwardly extending tongue part formed with an engaging face diagonal to the longitudinal line of the connector arm, but opposite to the diagonal air head engaging face, and means on the tongue part of the steam head engaging the flaring 60 guide member of the air head, said means causing the steam head to pivot on its axis to follow horizontal pivotal action of the air head. 65
7. In a train pipe connector, the combination of a horizontally extending connector arm, a knuckle mounting on the forward end of said 70 arm, an air pipe connector head mounted to pivot on a vertical axis on said knuckle mounting, said air pipe connector head having a forwardly projecting tongue part formed with an engaging face diagonal to the longitudinal line 75

of the connector arm, and having on the side of said engaging face a flaring guide member adapted to gather and receive the tongue part of an opposing air head, a steam pipe connector head below said air head pivotally mounted on said knuckle mounting on a vertical axis substantially coincident with the air head axis, said steam head having a forwardly extending tongue part formed with an engaging face diagonal to the longitudinal line of the connector arm, but opposite to the diagonal air head engaging face, and a pair of upwardly extending lugs on the tongue part of the steam head receiving therebetween a lower edge portion of the flaring guide member of the air head, whereby the steam head is caused to pivot on its axis to follow horizontal pivotal action of the air head.

8. In a train pipe connector, the combination of a horizontally extending connector arm, a knuckle mounting on the forward end of said arm, the upper end of said knuckle mounting being above said connector arm and having a forwardly projecting portion having an upwardly extending trunnion, said knuckle mounting having spaced below said first mentioned for-

wardly projecting portion, and below the connector arm, a second forwardly projecting portion, said last mentioned forwardly projecting portion having a vertical bore concentric with said trunnion, an air pipe connector head provided at its rearward end with a pair of vertically spaced rearward projections, the upper one of which has a vertical bore adapted to receive the knuckle trunnion, and the lower one of which has a downwardly extending trunnion adapted to 5 be received in the upper end of the vertical bore of the knuckle, a steam pipe connector head having at its rearward end a pair of upwardly and downwardly extending trunnions, said upwardly extending trunnion being adapted to be received 10 in the lower end of the vertical knuckle bore, and a supporting member demountably attached to the lower portion of the knuckle mounting and engaging and supporting the lower side of the rear end portion of the connector head, said supporting member having a vertical bore rotatably receiving the downwardly extending head trunnion.

CLIFTON B. HERD.
